UNITED STATES PATENT OFFICE

2,480,446

INSTRUMENT FOR THE TREATMENT OF
FINGERNAILSGustav A. Carlson, Chicago, Ill., assignor to The
Boye Needle Company, Chicago, Ill., a corpora-
tion of Illinois

Application March 30, 1945, Serial No. 585,644

2 Claims. (Cl. 132—73)

1

This invention relates to a combination instrument for the treatment of cuticle and finger nails, and more particularly to a device for pressing the cuticle about the finger nail toward the flesh of the finger and for cleaning finger nails.

An object of the invention is to provide a device having a thin, relatively sharp edge for pressing finger cuticle toward the flesh of the finger. Another object is to provide in a device having a thin, sharp-end edge, a cutaway portion on the under surface which permits the edge to be brought into engagement with the finger nail cuticle at a desired angle. A further object is to provide an instrument having an arcuate end portion, cut away on the lower side and provided with a thin, relatively sharp-end edge for engaging the cuticle.

Another object of the invention is to provide a device in which is combined means for engaging the cuticle on a finger nail and a sharp edge, angularly disposed with respect to the body of the device, for cleaning finger nails. Another object is to provide a device having an edge disposed at an acute angle with respect to the axis of the device for cleaning finger nails. Still another object is to provide in a device for cleaning finger nails, a plurality of sharp edges disposed at different acute angles with respect to the axis of the instrument.

Other features and advantages will appear from the following specification and drawings, in which—

Fig. 1 is a perspective view of an embodiment of the invention; Fig. 2 is a transverse sectional view taken along the line 2—2 of Fig. 1; and Fig. 3 is a side elevational view, partly in section, showing the same embodiment of the invention.

In the embodiment of the invention described herein, the device consists of a long body member 10, which may be round or circular in cross section and may be made of any suitable material. Preferably, the device is made of a resinous or plastic material which is hard, smooth, and on which the ends may be readily machined or cut to the desired shape. The material may be of any suitable color, and in the case of a resinous material the color may be introduced into the material before molding so as to provide uniform color throughout.

At one end of the body member 10 is an end portion 11 which is thin and extends to an end edge 12 which is relatively sharp. Preferably, as shown, the end portion 11 is arcuate in shape, with the upper surface 13 being curved downwardly as it approaches the end edge 12. The lower surface

5 14 may be cut away. Preferably, as shown, this lower surface 14 is also curved, and as it approaches the end edge 12 may curve first upwardly and then downwardly. At the end edge 12, the upper and lower surfaces 13 and 14 preferably approach parallel relation.

The end portion 11 may be made arcuate by machining or otherwise, forming upper and lower surfaces which are straight and flat in a plane transverse to the axis of the body member 10, but arcuate and curved in a vertical plane passing longitudinally through the axis of the body member 10.

10 15 The end edge 12 is preferably substantially transverse to the axis of the body member 10, but of course need not be right-angularly disposed with respect to this axis.

15 20 At the other end of the body member 10 is an edge portion 15 which is arranged to provide a plurality of longitudinal edges disposed at acute angles with respect to the axis of the body member 10. The end portion 15 may be provided with flat sides 16, 17 and 18 forming between them edges 19, 20 and 21. As shown, the angle formed 25 by the junction of these flat sides may in each case be in the neighborhood of 120°. However, any other desired angular relationship between the flat sides is suitable.

25 30 The edges 19, 20 and 21 are each disposed longitudinally at an acute angle with respect to the axis of the body member 10, and in each case this acute angle is different. This may be accomplished by merely extending the edges 19, 20 and 21 from the central axis of the body member 10 at the point 22 to the various portions 23, 24 and 25 along the body member 10. Since the radial distance between the two ends of each edge is the same by making the edges of different longitudinal distances or lengths, the angles of the edges with respect to the axis of the body member are necessarily different.

35 40 Instead of three edges, any desired plurality of edges may be used, and the angular relationship of the two sides which form each edge and the angular relationship of the edge and the axis of the body member 10 may be varied as desired.

45 50 In use, the end portion 11 of the body member 10 is designed for engaging the cuticle on a finger nail and pressing the cuticle toward the flesh of the finger. The body member 10 may be placed above the finger nail at a very slight angle with respect to the finger nail and the edge 12 brought into engagement with the cuticle. By merely pressing the edge against the cuticle, the cuticle is moved toward the flesh of the fin-

ger. The cutaway portion 14 permits the body member 10 to be nearly parallel to the surface of the finger nail while permitting the edge to engage the cuticle.

In the cleaning of finger nails, the end portion 15 is placed beneath the finger nail. One of the edges 19, 20 or 21 is brought into engagement with the under surface of the nail. The edge which is used will be that which corresponds most closely in its angular relationship with respect to the axis of the member 10 to the angular relationship between the under surface of the finger nail and the finger. By providing cleaning edges arranged at different angles with respect to the body member, a cleaning edge particularly suited for various types of nails is available for use.

By reason of the triangular disposition of the cleaning edges 19, 20 and 21, the surface opposite each of these edges is flat and substantially parallel to the finger surface beneath the nail. This is an advantage of the triangular disposition of the cleaning edges which makes this arrangement preferred.

Cotton or other similar soft material may be placed on the end 15 of the instrument, and this end bearing cotton may then be used for cleaning particles of cuticle from the nail or for removing excess nail polish on the nail or portions of the finger adjoining the nail. The cotton may be used either wet or dry. In any event, the triangular construction of the end 15, with the sharp edges provided thereby, aids in retaining the cotton on the end when it is used in this manner.

Although the invention has been described in connection with certain specific embodiments, it will be apparent that modifications and changes may be made without departing from the spirit and scope of the invention.

I claim:

1. A device for the treatment of finger nails comprising a body member having an end portion provided with a plurality of flat sides providing between them longitudinal sharp edges, each of said sides being diametrically opposed to one of said edges, the distance between one edge of the flat side opposite thereto being different from the distance between another edge and the flat side diametrically opposite thereto.

2. A device for the treatment of finger nails, comprising a generally circular body member having an end portion provided with a plurality of flat sides, providing between them longitudinal edges, each of said sides being diametrically opposed to one of said edges, and the distance between each edge and the flat side opposite thereto being different from the distances between the other edges and flat sides opposite thereto.
